US0D1042219S

(12) United States Design Patent (10) Patent No.: US D1,042,219 S
(45) Date of Patent: * Sep. 17, 2024

(54) ORNAMENT

(71) Applicant: Jinze Liu, Henan (CN)

(72) Inventor: Jinze Liu, Henan (CN)

() Term: 15 Years

(21) Appl. No.: 29/913,975

(22) Filed: Oct. 11, 2023

(30) Foreign Application Priority Data

Apr. 28, 2023 (CN) 202330250486.4

(51) LOC (14) Cl. 11-02

(52) U.S. Cl.

USPC D11/157

(58) Field of Classification Search

USPC D11/126-129, 149-150, 157-158, 160,
D11/164; D21/576, 621, 631, 633, 659;

(57) CLAIM

The ornamental design for an ornament, as shown and described.

DESCRIPTION

FIG. 1 is a front, right and top perspective view of an ornament, showing my new design;

FIG. 2 is a rear, left, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and top perspective view thereof, showing the ornament is an alternate state.

The broken lines in the drawings represent portions of the ornament that form no part of the claimed design.

1 Claim, 9 Drawing Sheets
